UNITED STATES PATENT OFFICE.

GEORGE ERNEST BRITTAINE, OF HAVERHILL, MASSACHUSETTS, ASSIGNEE TO IRVING L. KEITH, OF HAVERHILL, MASSACHUSETTS.

LEATHER-SKIVING MACHINE.

Application filed February 24, 1920. Serial No. 360,623.

To all whom it may concern:

Be it known that I, GEORGE E. BRITTAINE, a citizen of the United States, and a resident of Haverhill, county of Essex, State of Massachusetts, have invented an Improvement 5 in Leather-Skiving Machines, of which the following is a specification.

This invention relates to machines for skiving or splitting leather, the preferred 10 embodiment of which, hereinafter described, is more particularly adapted for leather skiving, and is of the type having a fixed knife and means for feeding the work thereagainst.

15 In the manufacture of shoes, it is a well-known practice to skive the heel portion of a full length sole, before it is rounded, on a bevel, which is started on the flesh side near the rear end of the shank portion and ends 20 on the grain side close to the heel end, and to reconnect the severed pieces adhesively in such a position that the length of the sole will be substantially increased, usually by two sizes. As the sole thus lengthened will 25 still serve all practical purposes as well as before, a very substantial saving is thus made in the cost of the sole, and in spite of the labor involved, on account of the leather saved in cutting out a sole of one size as 30 compared with a sole two sizes larger.

In performing the skiving operation on soles in the manner above indicated, much difficulty has been encountered, which was 35 partly due to the fact that leather soles are frequently hard and brittle, so that they are difficult to cut and are liable to break or be torn when skiving is attempted.

For example, it is desirable to have the 40 skiving cut made on a long bevel and carried completely through to the grain surface, so that the edges, at the point of severance, will be as sharp as possible, but, with prior machines, great difficulty has been encountered due to breaking of the sole before the cut 45 was finished, and to the tendency of the knife to "dig in" on hard soles, and cut them on a short bevel.

In this connection, I have discovered that, 50 in order that satisfactory results may be secured, in skiving soles which are especially difficult to cut, it is necessary that the sole be held against the bed with a very strong force, by the time the knife has entered the sole to a substantial extent, and that this

pressure should be increased up to the point 55 where the knife cuts through the grain surface, at the end of the cut. Also, that when a spring was employed for such purpose, which was of sufficient strength to press the sole against the bed of the machine with the 60 desired force, the force required to bring the parts into the proper relation to start the skiving operation was too great to permit this to be done quickly and easily, with hand or foot operated levers, which could be conveniently employed for this purpose. 65

An object of my invention is to provide a machine, of the character above indicated, which is especially adapted to skive the heel end portions of soles in a rapid manner, and 70 to form flat, inclined surfaces thereon, so that, when the parts are attached adhesively in a different position, the attached surfaces will practically correspond.

A further object is to provide a machine 75 which will be of simple construction, and will be unlikely to get out of order, and in which this sole skiving operation may be rapidly performed.

I accomplish these objects by the means 80 shown in the accompanying drawings in which:—

Fig. 1 is a side elevation of a leather skiving machine embodying my invention.

Fig. 2 is a front elevation thereof.

Fig. 3 is a horizontal sectional view at line 85 3—3 of Fig. 1.

Figs. 4 and 5 are sectional views through the bed portion of the machine showing the position of the parts in different stages of 90 the operation.

Figs. 6, 7 and 8 are detail views.

As shown in the drawings, the side frames 10 are provided with vertical guideways 11 in which a pair of bearing boxes 12 are 95 mounted to slide vertically and a shaft 14 is journaled in said boxes and is provided with a driving pulley 16 on one end and a corrugated feed roll 18 at its intermediate portion, said shaft, in the normal operation of 100 the machine being driven at a constant speed in the direction of the arrow in Fig. 1.

The downward movement of the boxes 12 is limited by stop screws 13, at the bottom of the guideways, and upward movement of 105 said boxes is resisted by a pair of relatively light tension springs 15, which are disposed between said boxes and followers 17 on the

lower ends of adjusting screws 19, threaded in a cap piece 21, and by a pair of springs 23 of relatively heavy tension, which are arranged to enclose the springs 15, and act 5 to reinforce the resistance of the springs 15, as hereinafter more particularly described.

The bed of the machine comprises a segmental shaped rear plate 20 mounted, at its 10 ends, on radially disposed arms 22, to swing about a pivot shaft 24, the surface of said plate being curved from the center of said pivot shaft as a center. A smooth surfaced roll 26 is journaled in said arms 22 to rotate freely close to the front edge of said plate 20, said roll having reduced ends 26^a which pass through the arms 22, and being so arranged that the surface of the plate is slightly below a plane which would be 15 an exact tangent to the surface of the roll, as shown in Figs. 6 and 7, for reasons to be explained. The bed further comprises a front plate 28, having its surface curved on a radius of approximately the same length 20 as that of the plate 20, said plate 28 being provided with ears 29, which are apertured to receive the reduced ends 26^a of the roll 26, so that said plate is adapted to swing vertically about the axis of the roll 26 as 25 a center and has its surface practically tangent to the surface of said roll 26.

A rectangular shaped frame 30 is mounted to swing on a pivot shaft 32 beneath the plate 28 and is provided with a friction roll 34 at each corner, arranged to engage correspondingly located ribs 28^a on the under side of the plate 28. A sleeve 36 is fixed on a shaft 38, adjacent shaft 32, and is provided with an integral arm 40, which is pivotally connected to one end of a link 42, the opposite end of said link being pivotally connected to the frame 30, forming a toggle connection between shaft 38 and frame 30. A hand lever 44 is secured to 45 the outer end of the shaft 38 and a lug 45 with a screw 46 therein is secured on the frame 10 in position to limit the operative swinging movement of the lever 44.

A splitting or skiving knife 50 is secured 50 on the machine frame in position to extend beneath the feed roll 18, with its edge in a position somewhat in front of the vertical plane of the axis of the roll, and, under ordinary conditions, is set about $\frac{1}{8}$ th of an 55 inch above the level of a horizontal plane which is tangent to the surface of the feed-roll at its lowest point.

The arrangement is also such that when the knife is set in this position, its edge will 60 just clear, or will have a shearing action with the surface of the roll 26 in the bed, when the bed is swung to its extreme forward position, in which position the middle 65 of the roll 26 is directly beneath the knife edge.

Suitable means are provided for securing the knife in position to permit transverse adjustment thereof, as by bolts 52, which pass through elongated apertures in the ends of the knife, and abutting screws 70 54, which are threaded in lugs 56 in the frame and engage the back edge of the knife, to reinforce the clamping action of the bolts.

The frame is also provided with lugs 58, 75 in which screws 60 are threaded in position to engage the under side of the knife near its back edge, so that the inclination at which the knife is set may be conveniently adjusted. When the leather is very hard 80 and difficult to cut, it is sometimes necessary to raise the level of the knife edge to prevent the cut being made on too short a bevel. Special adjusting means may be provided for varying the level of the knife 85 edge, or it may be adjusted by the simple expedient of employing shims under the front portion of the knife where it is clamped. In case the edge of the knife is set higher, it will usually be necessary to 90 adjust the screws 13 to raise the feed roll correspondingly.

In practice, for sole skiving, the initial position of the roll 18, relative to the knife, will be approximately that already described, and shown in Figs. 1 and 4, and upward movement of the roll from this position will be resisted by springs 15, only, as the springs 23 are of such length that, when fully expanded, as they are when the 100 boxes 12 are supported by stop screws 13, they will be out of contact with the followers 17, but will be moved into contact therewith when the roll is raised so that its lowest point is approximately at the 105 level of the knife edge, or slightly (about $\frac{1}{32}$ "') above said level, at which point both pairs of springs will act to resist further upward movement of the feed roll.

A gage 72 is mounted for adjustment, to 110 and from the feed roll, on rods 74 secured in the rear side of the frame, so that it presents a vertical stop face to the end of a sole inserted between the bed and the feed roll.

The pivot 24, on which the bed swings, is arranged in front of the vertical line from the axis of the feed roll, and said bed is gravity actuated, in all positions to swing to its rearmost position, and an adjustable stop, consisting of a screw 76 in a bracket 77 is provided to limit its rearward movement. The forward swinging movement of the bed is limited by a stop screw 78 therein, which is arranged to strike against the 125 rear side of the frame when the latter has been swung forward to a position in which the bed-roll 26 is held in shearing relation with the edge of the knife, as before described. The length of the scarf which will 130

be cut will depend, other things being equal, on the adjustment of the rear stop 76. That is, the greater the distance which the bed moves before this roll reaches the knife, the 5 greater the length of the scarf.

The parts being in the position of Figs 1 and 4, and the roll 18 being constantly driven in the direction indicated, the operation is as follows:—a sole α , which has 10 not been rounded, is inserted, grain side down, from the front of the machine, between the bed and knife, until its heel end engages the surface of the gage 72, then the operator pulls the hand lever 44 toward the 15 front causing the toggle 40, 42 to swing up the frame 30 and thus swing up the bed plate section 28, on its pivot 26^a, so that the sole is lifted into contact with the feed-roll 18. Continued upward pressure on the 20 sole will then cause the feed roll to be lifted against the action of the relatively light tension springs 15 until the sole is brought into contact with the knife, and the knife is caused to enter the sole slightly. By this 25 movement the hand lever and parts operated thereby will be lifted to the dotted line position of Fig. 3, in which position the lever will be engaged with the stop screw 46, which will have been previously adjusted according to the thickness of the soles to be 30 operated on, so that further movement in this direction will be prevented.

By this time, the feed roll will be engaged with the sole with sufficient force to feed it 35 back towards the operator, and the frictional engagement between the sole and the bed will also be sufficient to cause the bed to be drawn forward with the sole.

As the bed moves forward, the hand lever 40 is held against its stop, thus supporting the plate 28 in a position which is inclined to its path of movement, so that, as it is advanced, its surface approaches the knife edge and reaches the level of the latter at 45 the end of the cutting operation. This action causes a constant lifting of the feed roll all of which, after the roll has been lifted, to the level of the knife, is against the action of both pairs of springs, and as 50 the heavy tension springs 23 act practically to their fullest extent as soon as they are compressed at all, the whole cutting operation is performed while the sole is pressed by a strong force against the bed. This arrangement, however, makes it unnecessary 55 for the operator to strengthen the toggle against the action of anything but the light tension springs 15.

It will be apparent that, as the sole is advanced, the knife, which is set on a slight 60 inclination, will cut into the sole more deeply and will cut through to the grain surface when the bed roll 26 has been carried into shearing relation with the knife edge, at which point the inclined cut will

be finished and the small piece α' will be severed from the rest of the sole, as indicated in Fig. 5. This cut will usually be finished at a short distance from the end of the sole at which time the end portion 70

of the severed piece α' will be pressed against the bed roll 26 by the feed roll, as shown in Fig. 5, and, as the bed roll will prevent appreciable frictional engagement between the piece and the bed, the feed roll 75 will throw the piece α' out over the knife.

In case the cut is finished at some distance from the sole end, if the surface of the rear plate 20 were level with the surface of the bed roll, the frictional engagement, of the 80 severed piece with said surface would be likely to be sufficient to prevent the feed roll from pushing out the piece onto the knife. To obviate this difficulty, the surface of rear plate 20 is made lower than 85 the tangential position to the bed roll, so that a severed piece of this form will be entirely supported on the bed roll as indicated in Fig. 6, permitting it to be discharged by the feed roll.

The stop 46 for the hand lever performs an important function by preventing further lifting of the bed plate 28 after the cut has been started, which would cause the knife to sink into the leather to a greater 90 extent for the distance moved, so that the cut would be made on a shorter bevel and be finished before the bed roll 26 reached the knife. It follows, therefore, that, by adjusting the stop 76, which determines the 100 starting position of the bed and by adjusting the stop 46 according to the thickness of the sole (which latter adjustment would only have to be changed for different lots of soles) the length of the scarf may be determined 105 with a great degree of accuracy. That is, results will be secured which are as uniform as the character of the work demands.

The weight of the bed is so disposed relative to its pivot 24, that its entire forward movement is against gravity action, which may be reinforced by a spring 79, so that, when the bed is in the cutting-off position of Fig. 5, it will swing back to its initial position, as soon as the sole piece α' is pushed 110 forward onto the knife, unless otherwise prevented from so doing.

When the sole piece α' becomes disengaged from the feed roll, the latter will no longer be sustained thereby, and, unless 115 means are provided to prevent it, the roll will be forced down into engagement with the bed, and prevent the return movement of the latter, as well as cause damage. To obviate such difficulty, a pair of very stiff 120 spring fingers 80 are secured to the surface of the rear plate 20 at each side thereof in position to extend from points in the rear of the bed roll 26, over the latter and over the front plate 28 to points opposite which the 125

feed roll cannot engage its surface under any condition. Smooth, annular surfaces, 18^a, are formed on the feed roll at each end, in position to be engaged by said fingers 80, when said feed roll becomes disengaged from the severed piece. When this takes place, the whole force of the springs on the feed roll will be transferred to the fingers 80, which are normally supported out of contact with the bed surface and are adapted to yield to some extent when the downward action on the roll 18 is transferred thereto, as indicated in Fig. 8. These spring fingers are made sufficiently stiff to cause a slight rebound of the feed roll after it strikes said fingers, so that the return movement of the bed will start while this rebound is taking place. The feed roll then immediately re-engages the fingers, which present downwardly inclined surfaces thereto, and is sustained thereby until the bed is retracted sufficiently to withdraw the fingers from beneath it, by which time the bearing boxes 12 thereof will be resting on the stop screws 13, so that the roll can have no further action on the bed to prevent its return movement.

With the above described machine, the skiving operation, above referred to, may be rapidly performed, the operator merely inserting the sole with one hand, pulling back the lever with the other, and then releasing the lever by the time the cut is finished, so that he may immediately pick up the severed piece and remove the sole, which he retains hold of during the whole of the operation.

While the herein disclosed embodiment of my invention has been shown and described as especially adapted for use in skiving soles, it will be apparent that the machine may be readily adapted for leather splitting, as well as skiving, as it would be merely necessary to readjust the knife, and the initial position of the feed roll to do this. That is, it would be necessary to adjust the knife to a horizontal position, and raise its cutting edge, and to adjust the screws 13, so as to raise the feed roll correspondingly.

In such case, the gage plate 72 would probably be removed and the work would be inserted from the rear side of the machine, if the cut was to be made from one end. The machine could thus be readily adapted for splitting off the grain side of soles for French heels.

55 I claim:

1. In a machine of the character described, a fixed knife, a bed beneath the knife, a vertically movable roll arranged to press the work against said bed in advance of said knife, a support arranged to limit the downward movement of the roll at a point to engage the work below the level of the knife, manually operated means to lift the bed to press the work against the roll and lift it into engagement with the knife, a light ten-

sion spring arranged to resist action to lift the roll from said supports and a relatively heavy tension spring arranged to be inoperative to resist such lifting action during the portion thereof in which the work is raised 70 into operative relation to the knife and operative to resist such action during the remaining portion of the lifting action.

2. In a machine of the character described, a fixed knife, a bed located beneath the knife, manually operated means to force the bed upwardly to press the work into engagement with the knife, a feed roll arranged for vertical movement in advance of said knife and limited in its downward 75 movement to engage the work below the level of the knife, a light tension spring operative to press said roll downwardly in all positions thereof and a heavy tension spring 80 operative to oppose movement of the roll after the roll has been lifted to an extent sufficient to engage the work with the knife and inoperative to oppose the previous portion of said lifting movement thereof.

3. In a leather skiving machine, a fixed 90 knife, a bed plate reciprocally movable beneath said knife to carry the work into engagement therewith, a freely rotatable, smooth-surfaced roll mounted at the rear end of said plate, and arranged to be moved 95 with said plate into shearing relation with said knife at the end of the forward movement of the plate, and a feed roll arranged to press the work against said plate in advance of the knife, and rotated to feed the 100 work towards the knife.

4. In a leather skiving machine, a fixed 105 knife, a bed plate reciprocally movable beneath said knife to carry the work into engagement therewith, a freely rotatable, smooth-surfaced roll mounted at the rear end of said plate, with the work supporting surface of the plate disposed in approximately tangential relation to the surface of the roll, and a feed roll arranged to press the work against said plate in advance of the knife, and adapted to be rotated to feed the work towards the knife.

5. In a leather skiving machine, a fixed 115 knife, a supporting member pivotally mounted beneath said knife, a bed plate pivotally connected at its rear end to said member to swing about an axis parallel to the knife edge, manually operated means to force said plate upwardly, a freely rotatable 120 roll journaled on said member and disposed in transverse relation to said plate at its pivoted end, said roll being arranged to be carried into shearing relation with said knife at the end of the operative movement of the 125 bed, and means to press the work against said bed plate in advance of the knife.

6. In a leather skiving machine, a fixed 130 knife, a supporting member pivotally mounted beneath said knife, a bed plate piv-

totally connected at its rear end to said member to swing about an axis parallel to the knife edge, manually operated means to force said plate upwardly, a freely rotatable 5 roll journaled on said member and disposed in transverse relation to said plate at its pivoted end, said roll being arranged to be carried into shearing relation with said knife at the end of the operative movement 10 of the bed, a feed roll arranged to press the work against the bed plate in advance of said knife, and means to rotate said roll to feed the work to the knife.

7. In a leather skiving machine, a fixed 15 knife, a pivotally mounted member, a bed plate pivotally connected to said member and arranged in operative relation with said knife, a smooth surfaced roll journaled in said member to rotate about the axis of the 20 pivotal connection between said plate and said member and movable therewith into shearing relation with the knife, said plate having its work supporting surface disposed in approximately tangential relation with 25 the surface of the roll, means to lift said plate to lift the work into engagement with said knife and a feed roll arranged to press the work against said bed plate and feed it to the knife.

30 8. In a leather skiving machine, a fixed knife, a bed comprising front and rear plates pivotally connected at adjacent ends, said rear plate being pivotally mounted in position to permit said plates to be oscillated 35 beneath the knife in operative relation thereto, a smooth surfaced roll disposed between said plates with its surface forming a portion of the work supporting surface of the bed and journaled in said rear plate in position 40 to be moved into shearing relation with said knife when the bed is moved to its forward position, means for pressing the work against said bed and means for swinging said front bed plate upwardly, to lift the 45 work thereon into engagement with the knife.

9. In a leather skiving machine, a fixed 50 knife, a feed roll disposed in front of said knife, springs for pressing said roll downwardly, said roll being limited in its downward movement at a point to engage the work beneath the level of the knife, a bed comprising a rear member pivotally supported beneath the knife, to swing towards 55 and from the knife, and a front member hinged to said rear member, means to swing said front member upwardly to lift the work thereon into engagement with said roll and knife, means to operate said roll to feed the work towards the knife, and supports 60 mounted on the rear member and extending over the front member in position to be engaged by said roll at its opposite ends in the advanced position of the bed, to sustain the 65 roll as it becomes disengaged from the work

and permit it to be gradually lowered, during the initial portion of the return movement of the bed.

10. In a leather skiving machine, a fixed 70 knife, a feed roll disposed in front of said knife, springs for pressing said roll downwardly, said roll being limited in its downward movement at a point to engage the work beneath the level of the knife, a bed comprising a rear member pivotally supported beneath the knife to swing towards and from the knife, and a front member hinged to said rear member, means to swing said front member upwardly to lift the work thereon into engagement with said roll and 80 knife, means to operate said roll to feed the work towards the knife, and a pair of spring fingers supported on said rear member and extending over said front member in position to be engaged by said roll at its opposite ends, when the bed is in its extreme forward position, to provide a yielding support for the roll, as it becomes disengaged from the work and during the initial portion of the return movement of the bed. 90

11. In a leather skiving machine, a fixed 95 knife, a feed roll disposed in front of said knife, springs for pressing said roll downwardly, said roll being limited in its downward movement at a point to engage the work beneath the level of the knife, a bed comprising a rear member pivotally supported beneath the knife, to swing towards and from the knife, and a front member hinged to said rear member, means to swing said 100 front member upwardly to lift the work thereon into engagement with said roll and knife, means to operate said roll to feed the work towards the knife, and a pair of fingers supported on said rear member and extending over said front member and formed to provide downwardly inclined surfaces arranged in position to be engaged by the roll, when the bed is in its advanced position and the roll becomes disengaged from the work. 110

12. In combination with a fixed knife, a bed-plate pivotally mounted beneath said knife, in position to be oscillated in operative relation thereto and constantly actuated to return from an advanced position to a 115 normally retracted position, a feed roll disposed in front of said knife and spring actuated to press the work against said bed plate, manually operated means to move said bed plate upwardly to lift the work thereon into engagement with said knife and feed roll, and means to rotate said roll to feed the work towards the knife, and move the bed-plate by the frictional engagement of 120 the work therewith.

13. In combination with a fixed knife, a bed pivoted in position to be oscillated in operating relation with the knife, and yieldingly actuated to be retracted from the knife to an initial position, an adjustable stop to 130

limit the retractive movement of said bed, a feed roll arranged in advance of the knife in position to press the work against the surface of the bed, means to rotate said roll 5 in a direction to feed the sole towards the knife and to actuate the bed in the same direction by the frictional engagement of the work therewith and an anti-friction device in the bed arranged to permit the roll 10 to disengage the work from the bed at the end of the cutting operation.

14. In combination with a fixed knife, a bed pivoted in position to be oscillated in operative relation with the knife, and yieldingly actuated to be retracted from the knife to an initial position, an adjustable stop to limit the retractive movement of said bed, a feed roll arranged in advance of the knife in position to press the work against the surface of the bed, means to rotate said roll in 15 a direction to feed the sole towards the knife and to actuate the bed in the same direction by the frictional engagement of the work therewith, and a freely rotatable roll mounted in the bed in position to support the work at the end of the cutting operation, to permit the feed roll to feed the work thereon, without substantial frictional engagement 20 with the bed and disengage the same therefrom.

15. In a leather skiving machine, a fixed knife, a bed mounted to oscillate beneath said knife in operative relation therewith

and having a portion thereof arranged to be advanced into shearing relation with the knife, means to limit the retractive movement of the bed, manually operated means to swing a portion of said bed upwardly to lift the work into engagement with the knife and having an adjustable stop to limit said lifting movement according to the thickness of the work, a feed roll yieldingly actuated to press the work against the bed in advance of the knife and rotated to feed the work towards the knife, and yieldingly actuated means constantly operative to return the bed to its rearmost position.

16. In combination with a fixed knife, a bed mounted to be oscillated beneath the knife in operative relation thereto, and comprising a front work-supporting plate, arranged to swing upwardly, to lift the work into engagement with the knife, an arm mounted to swing vertically beneath said plate, and having a friction roll at its free end arranged to be engaged therewith in all positions thereof, a manually operated lever arranged to swing said arm upwardly to lift said plate and a feed roll arranged to press the work against said plate in advance 50 of the knife and to be rotated to feed the work towards the knife.

In testimony whereof, I have signed my name to this specification.

GEORGE ERNEST BRITTAINE.
